UNITED STATES PATENT OFFICE.

FERDINAND SCHNEIDER, OF FULDA, GERMANY.

RECEIVING DEVICE FOR ELECTRIC WAVES.

Application filed November 16, 1921. Serial No. 515,468.

To all whom it may concern:

Be it known that I, FERDINAND SCHNEIDER, residing at Fulda, Germany, 16 Bahnhausstrasse, have invented certain new and 5 useful Improvements in Receiving Devices for Electric Waves, of which the following is a specification.

This invention relates to that class of receiving devices for damped or undamped 10 electric waves, in which a gap between electrodes is bridged over by means of a preferably spherical member of wave-reactive material, i. e. a crystalline substance which is responsive or sensitive to electric waves, 15 for example, silicon, molybdenum glance, pyrites, carborundum or the like, said wave-reactive member being subjected to pressure. I have found that members composed of such wave-reactive material have not a uniform 20 sensitiveness throughout and therefore I make said members movable along the electrode gap, preferably by means of rotation around their centres, this insures that the most sensitive points of the wave-reactive 25 member or members can be brought in contact with the electrodes.

Another feature of my invention consists 30 therein that the pressure exerted on the wave-reactive member or members is made adjustable whereby the effect may be increased. By roughening the edges of the electrodes in contact with the wave-reactive member, or by bending electrodes of sheet metal, I increase the number of points of 35 contact and finally I form the wave-reactive member or members from the most wave-sensitive parts of the reactive substance, which parts I ascertain by previous experiment. By this means the specific resistance 40 is considerably reduced, so that weak-current relays connected up can be used without the hitherto necessary intensifiers or extra sources of current, because speeches or sounds are received with a more powerful 45 and absolutely clear tone.

In the various typical embodiments of the receiving device according to the drawing illustrating this invention, Fig. 1 is a side elevation of the receiving device; Figs. 50 2 and 3 are plan views of electrodes arranged concentrically and eccentrically one within another forming a uniform gap and a gap of decreasing width; Figs. 4 and 5 are vertical sections through electrodes arranged one within another but having gaps 55 of different sectional shape; Fig. 6 is a sim-

ilar section through an embodiment in which the pressure plate of the wave reactive member serves as an electrode; Fig. 7 is a similar section with the wave reactive members held 60 in position by means of a carrier disc, without the application of pressure; Figs. 8, 9 and 10 show electrodes arranged side by side, with linear gaps, in side elevation and plan respectively, and Fig. 11 is a vertical 65 section through an embodiment in which a second analogous electrode system, is arranged above the first electrode system on the pressure plate.

As can be seen from Fig. 1 a bearing yoke 70 b is secured on the insulation plate a, and in this plate a are inserted the plugs c, d, which are in conductive connection with the screws e, f. These latter traverse the plate a and serve to secure the electrodes g, h, arranged one within another and resting on said plate. The bushing i, provided with a flange, is rotatably mounted in the bore s of the bearing yoke b, and is held in position by the retaining spring r, which engages in 75 the groove t and is secured to the yoke b. In the longitudinal bore of the bushing i slides the shaft of the circular pressure disc m of insulating material, the ascent and descent of which is restricted by the pin n in 80 the shaft of the disc m engaging a slot l of the bushing i. In the bushing i and above the shaft lies the spiral pressure spring o the tension of which can be adjusted by the screw p which is let into the head of the 85 bushing. A disc q secured on the upper end of the bushing i, enables the bushing i to be rotated by hand, and with it the disc m. The electrodes g, h are separated by the gap w, which is conductively bridged over by 90 the spherical wave reactive member k under the pressure of the disc m. The conductors u, v are connected to the plugs c, d. In Fig. 2 the gap w is of uniform width all the way round, but in Fig. 3 it is of decreasing width 95 towards one side. The gap w may have a rectangular edge (Fig. 4) or be beveled (Fig. 5).

In the embodiment according to Fig. 6, the electrode g has a groove of semicircular 105 cross section on its upper surface and the disc m is arranged as the counter electrode, being connected to the conductor v. In this case three points of unilateral conductivity come into operation, two on the grooved electrode g and one on the counter-electrode m. If the latter is also provided with a

groove a fourth point of unilateral conductivity is obtained. In the embodiment according to Fig. 7 the gap w is bridged over by two spheres k subjected only to their own weight, and the disc m holds the spheres k in two apertures even when they are shifted on the gap w by the rotation of the disc m .

In the embodiment according to Figs. 8 and 9, the electrodes g, h consist of two rods 10 arranged side by side, which may also be of disc shape and, as shown in Fig. 10, be employed in larger number. Here the electrodes g, h, g form the double gap $w-w$, which is bridged over by two spheres k . 15 The electrodes g, g are jointly connected to the conductor u , whilst the electrode h is connected to the conductor v . The electrodes whether constructed as rods or discs may also be arranged obliquely in relation 20 to each other, instead of parallel, thus making the gap or gaps w , convergent. Of course, means for pressing the spheres k could also be provided in these cases and such means could also be differently arranged 25 from that shown in Fig. 1.

In the embodiment according to Fig. 11, circular double electrodes g, h, g, h with double gaps, w, w and two spheres k , are employed, the circular insulating disk x , 30 to which is firmly secured the upper external electrode h , being secured to the disc m . In this case the upper and lower electrodes g, g are jointly connected to the conductor u , and the upper and lower electrodes h are 35 jointly connected to the conductor v ; and the opposed double electrodes g, h and the double gap w act with the spheres k as multiple contacts.

Of course, the essential features of the 40 invention are not affected if the members g, h are made of wave reactive material and the spheres k of metal or other suitable counter-electrode material. The wave reactive members k may, of course, have other 45 shapes than spherical.

The receiving device according to the invention operates in the following manner. On the reception of the electric waves these latter pass through the conductors u, c, e 50 and v, d, f (Fig. 1) to the two electrodes g and h . Since the gap w is closed by the spherical wave reactive member k , the disconnected oscillation circuit is also completed; and since the spheres k establish 55 contact, by their periphery, with the edges of the electrodes at two points, the current appears at both points of contact, which current can be utilized for operating a relay, or for receiving audible or written Morse 60 signals or for telephony or the audible reception of sounds. The contact pressure of the sphere k must be adjusted according to the rectifying medium selected. By turning the disc m by means of the disc q , the 65 sphere k is rotated, and rolls in the gap w

to the position of the desired maximum of unilateral conductivity. The unilateral conductivity can also be increased by making the electrodes g, h of sheet material with turned-up edges, the points of contact with the sphere k being increased by the alteration in structure or surface of the edges.

The unilateral conductivity may be similarly increased by roughening the edges of the electrodes. A further increase in sensitivity may be obtained by the employment of a gap of decreasing width according to Fig. 3 for example. When the sphere lies over the narrowest portion of the gap w , the maximum degree of sensitiveness is obtained, and at the same time the specific resistance of the receiver contacts is considerably reduced. The material of which the spherical rectifying member is composed naturally plays an important part. If a highly sensitive crystal be used as such in order to obtain a high efficiency, a single sphere will give the desired effect. By using several spheres, even with crystals hitherto considered as of low sensitiveness, a high efficiency is obtained combined with diminished specific resistance.

I claim:

1. A receiving device for damped and undamped electric waves consisting of electrodes leaving an intermediate gap, a spherical electric wave reactive member bridging over said electrode-gap and a means for moving said member along said gap imparting to it a rotation around its centre.

2. A receiving device for electric waves consisting of an annular electrode surrounding a circular electrode so as to leave an intermediate gap, a member reactive to electric waves bridging over said gap and a means for moving said member along said gap.

3. A receiving device for electric waves consisting of electrodes leaving an intermediate gap bridged over by a member reactive to electric waves and adapted to be moved along said gap and a rotatable disc holding said member and imparting to it said movement.

4. A receiving device for electric waves consisting of electrodes leaving an intermediate gap bridged over by a spherical member reactive to electric waves and adapted to be moved along said gap and a rotatable means standing under adjustable pressure of a spring for imparting said movement to said member.

5. A receiving device for electric waves consisting of electrodes leaving an intermediate gap, bridged over by a member reactive to electric waves and adapted to be moved along said gap and a rotatable disc standing under adjustable pressure of a spring for imparting said movement and said pressure to said member.

6. A receiving device for electric waves consisting of electrodes leaving an intermediate gap bridged over by a member reactive to electric waves and adapted to be moved along said gap, a rotatable disc standing under adjustable pressure of a spring for imparting said movement to said member, and a means for rotating said disc.

7. A receiving device for electric waves consisting of a circular electrode in fixed position, an annular electrode in fixed position surrounding said circular electrode so as to leave an intermediate gap, a spherical

member reactive to electric waves bridging over said gap, a rotatable disc resting on said member and provided with a shaft slidably mounted within a cylinder and engaging a slot of said cylinder by a laterally projecting pin, said cylinder being turnable with said shaft in a yoke, a screw-threaded spring within said cylinder above said shaft and a screw screwed in the upper end of said cylinder for adjusting the pressure of said spring on said shaft.

In testimony whereof I affix my signature.

FERDINAND SCHNEIDER.
